UNITED STATES PATENT OFFICE.

WALKER E. MARSHALL, OF SPRINGFIELD, OHIO, ASSIGNOR, BY DIRECT AND MESNE ASSIGNMENTS, OF FORTY-FIVE PER CENT TO ORIN C. BROWN, WILLIAM H. BOWERS, STEPNEY R. HAMLET, ALBERT BOWMAN, FRANK SCHAEFER, HARRY I. FLEMING, JAMES MASTERPOS, CHARLES H. SROUFE, AND CHARLES DAVIDSON, ALL OF SPRINGFIELD, OHIO.

LOCKING VALVE.

Application filed May 28, 1921. Serial No. 473,474.

To all whom it may concern:

Be it known that I, WALKER E. MARSHALL, a citizen of the United States, and a resident of the city of Springfield, county of Clark, 5 and State of Ohio, have invented certain new and useful Improvements in Locking Valves, of which the following is a specification.

My invention relates to an improved 10 locking valve of the type shown in my co-pending application for valves filed September 19, 1919, Serial No. 324,994 and for automobile attachments filed March 29, 1920, Serial No. 369,596, which is adapted to be 15 interposed between the carburetor and the intake manifold of an internal combustion motor, particularly automobile motors and which provides an effective means for preventing unauthorized use of a motor or 20 vehicle by cutting off the fuel supply to the motor.

My present invention consists in improvements in this type of locking valve which greatly simplifies its construction so that it 25 is more positive in operation and can be manufactured more quickly and cheaply.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side elevation of an internal combustion motor with my invention applied thereto;

Fig. 2 is a top view of the assembled valve ready to be applied to a motor;

Fig. 3 is a detail view of the slide;

Fig. 4 is a side view of the invention showing the valve stop in dotted lines;

Fig. 5 is a longitudinal section on line 5—5 of Fig. 4;

Fig. 6 is a vertical sectional view on the line 6—6 of Fig. 5;

Fig. 7 is a side elevation of a motor showing a modified form of my invention applied

to, and forming part of, the manifold thereof;

Fig. 8 is an end view of a manifold, partly in section, showing my modified form of invention forming a part thereof.

The invention is designed for use with 55 automobile motors and is preferably interposed between the intake manifold "X" and the carburetor "C" of such a motor as shown in Fig. 1. The invention is so constructed that it may be applied between the carburetor and intake manifold on either 60 side of the motor. The valve comprises a preferably cylindrical casing 1 open at one end and closed at the other and having oppositely disposed tangential flanges 2 and 3 on its peripheries and a suitably shaped port 4 extending through the flange 2 and adapted to communicate with the intake manifold 65 "X" of the motor when the flange 2 is secured to a similar flange on said manifold "X". The casing also has an oppositely 70 disposed port 5 extending through the flange 3 and adapted to communicate with the outlet of a carburetor when the flange 3 is secured to a similar flange on said carburetor. The casing 1 also has a radially 75 extending hollow boss 6 on its periphery intermediate the flanges 2 and 3 and near the open end of the casing. In the bore of the boss 6 is mounted a pin 7 which is normally projected into the casing 1 for a purpose hereinafter described by means of an 80 expansible spring 7^a mounted thereon, the lower end of the spring abutting against the flange 9 on said pin 7 and the upper end of the spring abutting against the threaded 85 shank 10 of a nut adapted to engage a threaded counter bore 6^a in said boss 6. The outer end of the pin 7 may have a cord (not shown) secured thereto so that same may be operated from a distance. The operative 90 parts of the valve are carried by a flanged cap 11 which is preferably cast with a bore 12 and a counter bore 13. Into the bore 12 is inserted a cylindrical lock housing 14 which contains a lock of a standard construction, the outer end of said housing 95

being provided with a flange 15 adapted to fit nicely into counter bore 13 so that the surface of the cap or disc 11 will be smooth and unbroken except for a keyhole into which is inserted the key for moving the valve into inoperative position as herein-after described. The housing 14 is exteriorly threaded on its inner end to permit a milled locking nut 16 to be screwed 10 tightly thereon securely fastening the housing 14 to the disc or cap 11. The housing 14 preferably has a rotatable post 17 mounted eccentrically on its inner face. The post 17 has a shoulder 18 and a reduced portion 15 19 through which is tapped a pin 20. Between the shoulder 18 and the pin 20 is mounted a collar 21. The collar 21 preferably has a radially extending pin 22. Attached to the pin 22 is one end of a helical 20 spring 23 which is mounted on the post 17, the other end of said spring being attached to a small lug 24 on the inner face of the housing 14 beside the post 17. The collar 21 also preferably has ears 21^a which engage the pin 20 to prevent the helical spring 23 from unwinding, but at the same time permitting the pin 22 to be oscillated on the post 17.

The pin 22 engages and actuates a slide 30 25. Said slide 25 consists of a curved plate having a hollow boss or socket 26 on its convexed surface intermediate its ends adapted to receive the pin 22. The slide 25 is preferably held in close engagement with 35 the inner wall of the casing by means of an expansible spring 27 in the socket 26 so that the slide will form a tight closure when in operative position. The spring 23 on the post 17 normally urges the pin 22 and the 40 slide 25 to closed position. The slide 25 is provided with a notch 28 which engages with the spring pin 7 in the casing 1 when the slide is turned to unlocked position by means of rotation of the post 17 by a suitable key and held in this position until the 45 pin 7 is disengaged from the notch 28; the helical spring then operates to close the slide 25. As before stated the cap or disc 11 carries the lock and slide actuating members, the slide being a separate piece but adapted to be engaged with the pin 22 before the mechanism is inserted into the casing 1. In addition I provide a preferably U shaped member 28' which helps to 50 retain the cap or disc 11 in the casing 1 and at the same time forms a stop for the slide 25. This member has one of its bent arms forked as shown at 29 so as to straddle the milled locking nut 16 and is adapted to be 55 secured in such position by means of pins driven into the disc 11 thus providing a complete and effective means for preventing the nut 16 from moving. The opposite arm of the U-shaped member is adapted to abut 60 against the wall of the casing 1 and is pro-

vided with threaded bores which are adapted to receive threaded screws 29' tapped through the abutting wall. The connecting arm 30 serves as a stop to limit the movement of the slide 25 when urged into closed position by the spring 23.

The flange cap or disc 11 is preferably cast slightly larger than the opening in the casing 1 so that when the cap carrying the parts is to be inserted thereinto it will have to be driven or forced, thereby firmly securing the cap 11 in the casing. The arm 30 is then secured to the opposite wall by means of the screws engaging sockets in said arm as above described and the heads of such screws may be chipped off and touched with a brazing iron, if desired. When assembled the slide 25 on the pin 22 is held in retracted position by the spring actuated pin 7. When it is desired to lock the device by closing the inlet opening of the manifold the spring pin 7 is withdrawn from the notch 28 in the slide 25 at which time the helical spring 23 forces the slide to locked position completely covering the inlet aperture of the manifold. The slide when in closed position abuts against the member 30 so that the slide cannot be forced past the aperture. The valve is then in closed locked position and effectually prevents the unauthorized use of the motor or vehicle. When it is desired to again use the motor the person having a key fitting the particular lock of the valve will insert the key into the lock and rotate the post 17 and slide 25 away from the intake opening until the notch 28 in the slide is engaged by the spring pin 7.

In Figs. 7 and 8, I have shown a modification of my invention, which is of value in that the valve is rendered even more inaccessible than any construction previously described. In this form of locking valve, I preferably employ an intake manifold X² cast with a housing 31 thereon, as shown in Fig. 8. The housing 31 is similar in all the respects to the casing 1 except that it is cast integral with the manifold. A boss 6 is provided to carry the spring releasing pin 7, and the disk 11, carrying lock housing 14, locking nut 16, post 17, spring 23, collar 21, arm 26, stop 30, and the other parts of the locking mechanism are the same as before described.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I

claim as new and desire to secure by Letters Patent is:

1. A device of the character described comprising a housing interposed in a conduit and having a passage therethrough; said housing having one side open; a valve mounted in said housing adapted to open and close said passage; a closure for the open side of said housing carrying mechanism normally urging said valve to closed position; means for limiting the closing movement of said valve, said limiting means being connected to said closure and to the far side of said housing; means for retaining said valve in position against said urging means; means for releasing said valve from said retaining means; and locking mechanism for returning said valve to retracted position.
2. A device of the character described comprising a housing interposed in a conduit and having a passage therethrough, said housing having one side open; a closure for the open side of said housing; a rotatable member on said closure having a stud thereon; a valve slidably mounted in said housing having means engaging said stud, there being resilient means disposed between said stud and said valve; means for normally urging said rotatable member in one direction; means secured to said closure extending through said housing and being secured to the far side of said housing, said member serving as a stop to limit the movement of said valve; and locking mechanism for returning said valve to retracted position.
3. A device of the character described comprising a valve casing having one end open; a closure for said casing, there being a threaded lock barrel extending through said cap; a member threaded on said barrel to hold same in position; and means for preventing reverse rotation of said member on said barrel.
4. A device of the character described comprising a valve casing having one end open; a closure for said casing, there being a threaded lock barrel extending through said cap; a member threaded on said barrel to hold same in position; and means for preventing reverse rotation of said member on said barrel, said means also holding said cap in position in said casing.
5. A device of the character described comprising a valve casing having one side open; a closure for said open side, a lock barrel extending through said cap and having a member threaded thereon to hold same in position; and a securing member having a forked portion straddling said threaded member to prevent reverse rotation thereof, the opposite end of said securing member being fastened to the far side of said casing.
6. A device of the character described comprising a valve casing having one side
- open; a closure for said valve casing; a valve mounted in said casing, means normally urging said valve to closed position; means secured to said closure and extending across and being secured to the far side of said casing and serving as a stop for said valve; and locking mechanism for returning said valve to retracted position.
7. In a device of the character described comprising a casting having ports therein open at one side; a cast flanged disc having a bore and a counter bore; a lock housing extending through said bore; a flange on said lock housing engaging said counter bore; threads on the inner end of said lock housing; a locking nut engaging said threads to lock the housing to said disc; a rotatable post on said housing; a shoulder and a reduced portion on said post; a pin tapped through the reduced portion of said post; a collar mounted between said shoulder and said pin; an arm on said collar; ears on said collar engaging said pin to prevent rotation but permit oscillation of said collar; a helical spring mounted on said post and attached to the arm on the collar and to a lug on the lock housing, a slide operable by said arm to close the port therein, said helical spring normally urging the arm and slide to closed position, and a stop member adjacent said port to limit the movement of said slide one end of the said member being secured to the disc the other end of said member being secured to the opposite side, substantially as described.
8. In a device of the character described comprising a casting having ports therein open at one side; a cast flanged disc having a bore and a counter bore; a lock housing extending through said bore; a flange on said lock housing engaging said counter bore; threads on the inner end of said lock housing; a locking nut engaging said threads to lock the housing to said disc; a rotatable post on said housing; a shoulder and a reduced portion on said post; a pin tapped through the reduced portion of said post; a collar mounted between said shoulder and said pin; an arm on said collar; ears on said collar engaging said pin to prevent rotation but permit oscillation of said collar; a helical spring mounted on said post and attached to the arm on the collar and to a lug on the lock housing, a slide operable by said arm to close the port therein, said helical spring normally urging the arm and slide to closed position, and a stop member adjacent said port to limit the movement of said slide one end of the said member being secured to the disc the other end of said member being secured to the opposite side, substantially as described.
9. In combination with an intake mani-

fold having a housing cast integral therewith and open at one side; a cast flanged disc for closing said opening and having a bore and a counter bore; a lock housing 5 extending through said bore; a flange on said lock housing engaging said counter bore; threads on the inner end of said lock housing; a locking nut engaging said threads to lock the housing to said disc; a rotatable post on 10 said housing; a shoulder and a reduced portion on said post; a pin tapped through the reduced portion of said post; a collar mounted between said shoulder and said pin; an arm on said collar; ears on said collar 15 engaging said pin to prevent rotation but permit oscillation of said collar; a helical spring mounted on said post and attached to the arm on the collar and to a lug on the lock housing, a slide operable by 20 said arm to close the port therein, said helical spring normally urging the arm and slide to closed position, and a stop for said slide adjacent the port having a forked end adapted to be secured to the disc adjacent 25 to and engaging said locking nut to prevent rotation thereof, and the opposite end of said stop being secured to the opposite wall, substantially as described.

10. A device of the character described 30 comprising a valve casing having an open side; a closure member for said open side; and means secured to said closure member and extending across and being secured to the opposite inner wall of said casing for 35 holding said closure member in position.

11. A device of the character described comprising a valve casing having an open side; a closure member for said open side; and means secured to said closure member 40 and extending across, and being secured to the opposite inner wall of said casing for holding said closure member in position, said means being offset so as to lie against the wall of said casing.

45 12. A device of the character described comprising a valve casing having one side open; a closure for said open side; a valve mounted in said casing; means normally urging said valve to closed position; and means secured to said closure, and extending 50 across said casing and being secured to the far side thereof, said means serving as a stop for said valve.

13. A device of the character described 55 comprising a valve casing having a passage therethrough; a valve mounted in said casing adapted to open and close said passage; key operable means extending into said casing; an operative connection between said valve and said key operable 60 means, which connection permits play between said key operable means and said valve; means normally urging said valve to closed position; and means for engaging 65 said valve when turned to open position;

and means for releasing said engaging means.

14. A device of the character described comprising a valve casing having a passage therethrough; a valve mounted in said casing adapted to open and close said passage; key operable means extending into said casing, there being a post on said means having a reduced portion providing a shoulder and a pin extending through said reduced portion; a collar mounted between said shoulder and said pin, said collar having ears engaging said pin; and an arm on said collar for operating said valve. 70 75

15. A device of the character described comprising a valve casing having a passage therethrough; a valve mounted in said casing adapted to open and close said passage; key operable means extending into said casing, there being a post on said means having a reduced portion providing a shoulder and a pin extending through said reduced portion; a collar mounted between said shoulder and said pin, said collar having ears engaging said pin and an arm on said collar for operating said valve; means for normally urging said valve to closed position; means for engaging said valve for holding the same in open position; and means for releasing said holding means. 80 85 90 95

16. A device of the character described comprising a valve casing having a passage therethrough; a valve mounted in said casing adapted to open and close said passage; key operable means extending into said casing; a rotatable post mounted on said key operable means; a collar mounted for oscillation on said post; said collar having an arm operatively connected with said valve; and a spring connected to said key operable 100 105 means and to said collar for normally holding said valve in closed position.

17. A device of the character described comprising a valve casing having a passage therethrough; a valve mounted in said casing adapted to open and close said passage; key operable means extending into said casing; a rotatable post mounted on said key operable means; a collar mounted for oscillation on said post; said collar having an arm operatively connected with said valve; a spring connected to said key operable means and to said collar for normally holding said valve in closed position; means for engaging said valve when turned to open position; and means for releasing said engaging means. 110 115 120

18. A device of the character described comprising a valve casing having a passage therethrough, one side of said casing being open; a closure for said open side; a valve mounted in said casing adapted to open and close said passage; key operable means extending into said casing, said means including a post rotatably mounted thereon; a col- 125 130

lar mounted for oscillation on said post, and operatively connected with said valve; means for normally urging said valve to closed position; and means connected to said closure and extending across and being secured to the far side of said casing, said means serving as a stop for said valve.

In testimony whereof I have signed my name to this specification in the presence of two subscribing witnesses.

WALKER E. MARSHALL.
